UNITED STATES PATENT OFFICE.

EDWARD E. CLEMENT, OF WASHINGTON, DISTRICT OF COLUMBIA, ASSIGNOR TO

EDWARD F. COLLADAY, OF WASHINGTON, DISTRICT OF COLUMBIA,

TRUNKING SYSTEM FOR RADIO DISTRIBUTION.

Application filed March 15, 1926. Serial No. 94,850.

The present invention is a continuation in part of my copending application, Serial No. 3,861, filed January 21, 1925 patented March 16, 1926, No. 1,577,108. It relates to systems of radio broadcast distribution, and has for its object to organize such a system so that a program may be originated, relayed and distributed over a large area, uniformly and in a systematic and orderly manner to authorized users or subscribers who will get the full benefit of the use of vacuum tubes in receiving and amplifying without the necessity of maintaining tubes at their stations, the tubes used by the subscribers in receiving being located at central points where supervision, maintenance, power supply and control may be centralized and put under the care of expert operators.

In the second application above referred to, both relay distribution and supervision of the broadcast service for a group of subscribers is carried on at the central station or exchange local to the group. The subject of the present application differs from the aforesaid in that a district relay station, common to several subscribers' central stations, is provided for receiving broadcast matter for the central stations by radio, the central stations distributing the broadcast matter to their respective subscribers by wire, while supervision of the reception at the central stations is had at the district relay station over individual telephone lines and trunks connecting the district relay station with the different central or local distributing stations.

The invention is applicable to manual automatic or so-called semi-automatic or automanual telephone systems, the principles involved not being changed by different methods of effecting or controlling the necessary electrical switching connections.

My invention is illustrated in the accompanying drawings, in which:

Figs. 1 and 2 indicate diagrammatically, the telephone exchange portion and the broadcast distributing portion of a subscriber's central station forming part of my system.

Fig. 3 is a diagrammatic representation of a district studio and radio relay station.

Fig. 4 is a schematic diagram showing the system as applied to a district containing several local or exchange groups.

Fig. 5 is a diagram showing an arrange-

ment of circuits and apparatus affording selection of a plurality of programs.

Fig. 6 is a modification of the arrangement of Fig. 2.

Fig. 7 is a modification of the arrangement of Fig. 3, adapted to cooperate with the arrangement of Fig. 6.

Referring to the drawings in detail and first to Fig. 1, this shows the essential circuits of an ordinary telephone exchange system, in which J-J' are line terminal jacks forming the terminals of telephone lines leading to stations to be interconnected such as the subscriber's station A'. These jacks are arranged to be interconnected through the usual answering and calling plugs P-P' forming the terminals of the usual common battery cord circuit shown. The central office terminals of each line are provided with the usual line relay L¹, line lamp L² and cut-off relay L³. Where service is to be metered a recording meter M is also individually associated with the line. Thus, the circuit arrangement here shown is that of the standard multiple switchboard, common battery, telephone exchange system, and as such is well understood in the art further detailed description thereof will be here deferred and brought out later in the description of operation. In addition to the usual line terminal, multiples 1, 2 and 3, representing multiples of the tip, sleeve and test or cut-off circuits, respectively, I provide a fourth conductor 4 leading from a contact on the line relay along with the multiple conductors 1, 2 and 3 to the broadcast distributing system diagrammed in Fig. 2.

Fig. 2 shows the broadcast distributing system of which the portion to the left of the dotted line is situated at the central office and connected with the subscriber's telephone line terminal apparatus of the telephone central C (Fig. 1) through conductors 1, 2, 3 and 4, while the portion to the right of the dotted line in Fig. 2 is situated at the subscriber's substation and connected with the subscriber's telephone substation apparatus A' (Fig. 1) through the multiple conductors 5 and 6. In Fig. 2 the subscriber's line multiples 1-2 terminate in the spring contacts 7-8 of a jack 9 which contacts are arranged upon the insertion of the dummy plug 10 to be spread apart to engage with the stationary contacts 11-12 to extend the connection of the multiples 1-2 to conductors 11

13—14. The conductor 13 connects with the positive terminal of the common central office battery B through the winding 15 of a repeating coil 19 while the conductor 14 connects with the negative terminal of the battery 3 through a sleeve or supervisory relay 42 and the winding 16 of a repeating coil 20. An audion tube 37, individual to the line, is also provided which is arranged 10 with its output or plate circuit conductors 21—22 connected in series with the windings 17 and 18 of the repeating coils 19 and 20 and a plate battery B'. The input circuit of the tube 37 is arranged to be connected through contacts 23—24 on the supervisory relay 42 and conductors 25—26 to the program busses 27—28 to which are connected the audio output terminals of the radio receiver or broadcast relay and distributor 29 which may be of any known or other suitable type of radio receiver capable of furnishing the busses 27—28 with audio signaling currents of sufficient strength to supply the input circuits of the several subscribers' line tubes 37, it being understood 25 that several such line tubes (not shown) are supplied from the common busses as indicated by the multiple branch conductors 30. A normally closed contact 31 on the relay 30 42 connects the common battery B to the conductor 32 which terminates in a normally open contact 33 in the jack 9 operable to extend the connection of conductor 32 to the signaling conductor 4 to supply battery potential thereto. This signal conductor is arranged to be connected with battery upon energization of the subscriber's line relay through the line relay contact 52, Fig. 1. The relay 42, Fig. 2, also controls the connection of the multiple test circuit conductor 3 to the common battery B through a normally open contact 34 which connection includes a special tone test device of any known or other suitable form, indicated diagrammatically at 35, operable to superpose a characteristic signal current on the test conductor 3. Connected between the signal conductor 4 and ground is a signal lamp 36 mounted near the jack 9 in the manner 50 of the usual telephone line or call lamp.

In Fig. 3, which shows the equipment at the district or relay station, the radio relay apparatus indicated diagrammatically at 39 may be of any known or other suitable form 55 operable to receive radio broadcast matter from one or more distant stations and relay the same to the several subscribers' central distributing stations like that of Fig. 2. These district stations are preferably also 60 provided with means for originating broadcast matter, for example, a microphone 40 and modulator 41 connected with the relay apparatus.

A telephone trunk 101—102 connects the 65 district station Fig. 3, with the central sta-

tion Figs. 1 and 2, which trunk terminates in a jack 38 at the district station, Fig. 3, and in the usual line terminal apparatus 43 at the central station Fig. 1, which line terminal apparatus is the same in all respects as that of the subscriber A'. This terminal apparatus, like that of the substation A', is provided with multiple conductors 221, 222, 223 and a signaling conductor 224 corresponding in function to the conductors 1, 2, 3 and 4 respectively, of the substation A', leading to broadcast line terminal equipment not shown but similar in all respects to that shown in Fig. 1 associated with the line terminals of the substation A'.

Other jacks 44 and 45 at the district station form the terminals of other telephone trunks 201—202 and 301—303 connecting with other central stations like that of Figs. 1 and 2. Any of the lines 101—102, 201—202, etc. may be connected with the supervisory telephone set 46 through the plug 47 and the respective line jacks 38, 44, etc. Any of the lines 101—102 etc. may be also 90 operatively connected with the modulator 41 through the plug 48 and their associated line jacks 38, etc. To effect other combinations of connections between the jacks 38, etc. the modulator 41 and telephone set 46, the said jacks are connected with multiple jacks 138, etc., and connecting cords or link circuits such as 49 provided for connecting one or more lines to either or both the modulator and telephone set.

In addition to the ordinary telephone lines 101—102, etc., the district station is connected with the broadcast distributing portion, (Fig. 2) of the central station through a pair of test circuits comprising a test trunk 150—151 and an order circuit 152—153. The test trunk is a simple normally disconnected two wire circuit terminating at both ends in simple jacks 50 and 51. The order circuit 152—153 terminates at the 110 district station in a jack 73 and at the central station in a jack 73 and the usual common battery line terminal apparatus 54 with line lamp 55, the jacks 51, 73 and lamp 55 being located before an operator at the central station equipped with means for communicating with an operator at the district station which means may be an ordinary common battery cord circuit indicated symbolically at 56 (Fig. 2), and means for connecting the test trunk with the broadcast busses 27—28 which latter means is here shown as a simple plug and cord, link circuit 57 for connecting the jack 51 with a jack 58 connected with the busses 27—28. At the district station, Fig. 3, an operator's testing apparatus 59 is arranged to be connected with the test trunk through a plug 80 and the jack 50. Other pairs of test trunks and order circuits 161—162, 163—164, etc. extend 125 115 120 130

from the district station to other central stations equipped like that of Figs. 1 and 2, said trunks and order circuits terminating at the district station in jacks 81, 83, etc. situated with the jacks 50, 72, before the test operator and accessible to the plug 80. To enable tests to be made of a relay apparatus at the central office with all lines disconnected therefrom but without interrupting the service, the central office may be provided with a duplicate relay apparatus 89 arranged to be connected to the busses 27-28 by closure of a switch 70 when the apparatus 29 is disconnected by opening the switch 71, for test purposes.

Before proceeding with the description of operation of the system a broader view of the system is advantageous and may be had by reference to Fig. 4 wherein the district station 38 is indicated as being operatively associated with several local groups or subscribers' distributing centers 91, 92 and 93, each equipped as indicated in Figs. 1 and 2. The district station is arranged to receive broadcast matter from any distant station and relay the same by radio to the several subscribers' distributing central stations 91, 92 and 93 as indicated by the arrows adjacent to the antenna symbols on the several stations. The station 91 represents the station diagrammed in Figs. 1 and 2 while the substation A' represents the station A' of Figs. 1 and 2. Also the various lines and trunks 69-70, 150-151, 152-153, etc. represent those correspondingly numbered in Figs. 1, 2 and 3.

In operation, broadcast matter is transmitted from the district station (Fig. 3) by radio to the relay apparatus at the different central stations such as the relay and distributor 29 (Fig. 2), the audio output circuit of which is connected through switch 71 to the busses 27-28. A subscriber at substation A' desiring broadcast service, now connects his broadcast receiving or extension set A¹⁰ to the line by inserting the receiver plug P² in the jack J² which connects his receiver 64 across the line multiples 5 and 6 through the booster coil windings 60-65 and condenser 66 in series, and closes a path for direct current between the multiples 5 and 6 through coil 60, lower spring of jack J², transmitter 62 and signaling key 63.

This energizes the subscriber's line relay at the central office in the usual manner by current from the central office, common battery B, conductor 68, right hand winding of relay L', line conductor 69, to subscriber's substation A', line multiple 5, to subscriber's broadcast receiving set A¹⁰ (Fig. 2), coil 60, transmitter 62, contacts of key 63, conductor 6, 70, left hand winding of line relay L' and back to battery B. Actuation of the line relay energizes the line lamp L² by closure of a local circuit which may be traced

from common battery B through circuit elements L², 71, 68, and back to battery B. This causes the line lamp L² at the telephone operator's switchboard to glow, but only for a moment, as the subscriber wanting broadcast service will immediately operate his signal key 63 to rapidly open and close his line circuit which causes his line lamp to flicker instead of glowing steadily and so indicate to the telephone operator (Fig. 1) that the subscriber is not calling for a telephone connection. This intermittent actuation of the subscriber's telephone line relay L' also causes a flickering of the lamp 36 (Fig. 2) associated with his broadcast service, multiple jack 9 situated before the broadcast service operator. This operator perceiving the flickering of the lamp interprets the signal as a call for broadcast service and in answer thereto inserts the actuating plug 10 in the jack 9. This effects the closure of contacts 7-11, 8-12, and 33. Closure of the contacts 7-11, 8-12, connects the battery B (Fig. 2) across the subscriber's line through the repeating coil windings 15-16 and the sleeve supervisory relay 42 which connection may be traced from battery B (Fig. 2) through circuit elements 15, 13, 11, 7, 1, (into Fig. 1), 69, 5, (into Fig. 2), 60, 62, 6, (into Fig. 1), 70, 2, (into Fig. 2), 8-12, 14, 42, 16, back to battery B. As this completes the circuit including the battery B and the relay 42, this relay is energized and closes the circuit of the cut-off relay L² (Fig. 1) over a path which may be traced from the common battery B (Fig. 2) through the circuit elements 35, 34, 3, (into Fig. 1), cut-off relay L², 68, and through ground back to common battery B. Energization of the cut-off relay disconnects the subscriber's line from the telephone line signal apparatus in the usual manner, thus causing the line lamp L' to become deenergized and extinguishing both signal lamps L² and 36. As the cut-off relay is held energized over the test conductor 3 by battery supplied thereto through the special tone test device 35, a telephone operator in testing the line, will receive this characteristic tone test instead of the usual click in the ear indicating that the subscriber's line is busy with the special or broadcast service which may or may not be interrupted for telephone service according to the wishes of the subscriber.

Energization of the relay 42 (Fig. 2) also connects the input circuit of the subscriber's line tube 37 to the broadcast busses 27-28 by way of contacts 23, 24 and conductors 25, 26, respectively. The actuation of relay 42 also energizes the subscriber's line lamp 37 by closure of its filament circuits through contact 351, and filament battery F². The plate circuit of the tube 37 is energized from battery B through the plate circuit conductors 21, 22 and repeating coil windings 125

17 and 18. Thus the broadcast matter supplied to the input circuit of the tube 37 from the busses 27-28 is amplified in the output circuit 22, 18, B⁶, 17, 21, and transferred into the subscriber's line circuit by the repeating coil windings 15-16 included in the line circuit. The broadcast signal currents passing through the winding 60 of the booster coil 61 are repeated in the coil 65 and included in circuit with the subscriber's broadcast telephone receiver 64 which circuit may be traced from the coil 65 through circuit elements J², P², 64, P², J², 89, 62, 63, 266, back to coil 65. When the subscriber desires to discontinue the use of the broadcast service, the plug P² (Fig. 2) is pulled which opens the line circuit at the jack 9 deenergizing the relay 42, which in turn connects the battery to the signal circuit conductor 4 through relay contact 31 and energizes the radio service signal lamp 36 over a circuit which may be traced from common battery B through circuit elements 31, 32, 33, 4, 36 to ground and back to common battery B. This causes the lamp 36 to glow steadily indicating to the broadcast service operator that a disconnection is desired whereupon the operator pulls the plug 10 which opens all the contacts of jack 9 and restores the circuits to normal.

When it is desired to originate broadcast matter at the district station (Fig. 3), microphone 40 is used which operates through a modulator and transmitting portion of the radio relay 39, the circuits and apparatus of which modulator and transmitting portion of the relay being of any known or other suitable type. Where it is desired to permit a subscriber to broadcast from his station he may be connected through the ordinary telephone exchange circuit (Fig. 1) to the telephone line circuit 101-102 terminating in the multiple jacks 38 and 138 at the district station (Fig. 3) from which the connection may be extended by plug 48 to the modulator of the relay transmitter 39. To enable the operator at the district station to listen in on the broadcasting subscriber's line, the listening set 46 may be connected to the line through the plug 47 and the remaining one of the multiple jacks 38 and 138.

A test of the quality of reception at the central station (Fig. 2) may be had from the district station (Fig. 3) over the testing trunk 150-151 through the jack and the plug connection 50 and 47, and the listening set 46, the testing trunk having been connected with the output of the receiver 29 (Fig. 2) through jacks 51 and 72, and the link circuit 57. If it is desired that this test be made on the output of the receiver 29 free of all subscribers' line connections, a duplicate relay transmitting apparatus 89 may be put into service and connected to

the distributing busses by closure of switch 70 before opening the switch 71 to clear the apparatus 29, thus preventing interruption of the broadcast service. Other tests of the output circuit or other portions of the apparatus at the central station may be made over the test trunk by connecting the operator's testing apparatus 59 (Fig. 3) through the plug 80 and jack 50 to the test trunk, it being understood that the apparatus 59 may consist of suitable testing or measuring instruments such as a source or sources of current, ammeters, voltmeters, etc. In making these tests, the operator at the district station makes use of his listening set 46 and the order circuit 152-153 to communicate with the operator having charge of the broadcast receiving apparatus at the central station, so that the latter operator may set up the various circuit connections necessary to make the tests.

I have illustrated and described herein up to this point, a system in which a single broadcast relay apparatus is provided at the relay station shown in Fig. 3, and a single program bus 27-28 with single line switches or jacks 9 at the central distributing stations. It is of course obvious that these elements may be multiplied, that is to say, that the relay distributing station shown in Fig. 3 may be equipped to receive simultaneously from several sending stations, or may be equipped to receive from one or more sending stations and simultaneously to originate matter for distribution among the several district central stations shown in Fig. 2. Each central station would then have a number of receiving instruments 29, adapted to receive the different programs, and the output of each of these receiving instruments would be communicated to a separate trunk so that there would be a number of program trunks similar to that shown in Fig. 2 at 27-28, to any of which the subscribers may have access. For this purpose, the switching apparatus disclosed in my two prior copending applications, Serial No. 754,406, filed December 6, 1924, and Serial No. 913, filed January 6, 1925 may be employed. A simple form of selective apparatus working in conjunction with the line switch 9 is shown herein in Fig. 5. In the arrangement of this figure, the subscriber calls as before giving one long closure for a telephone call, and a series of short flashes for a radio call. This may be done by means of a key 63 (Fig. 2) or the ordinary automatic "sender" well known to those skilled in the telephone art. At the telephone station A' of Fig. 1, it is unnecessary to have any key or keys to secure telephone connection, it is only necessary to remove the receiver from the switch-hook, as usual, this producing a continuous make, as at present.

Referring to Fig. 5, the parts are exactly as in Fig. 2, with exception that a selective switch S is provided, stepped around by means of an electromagnet 420, controlled through front contacts 310 of the relay 42 which is included in the line circuit of battery B when the contacts of the line switch 9 are closed by the radio operator. The selective switch S contains bank contacts s — s' — s'' connected to separate busses 27—28 (carrying No. 1 program), 270—280 (carrying No. 2 program), and 2700—2800 (carrying No. 0 or announcements). The switch S does not need to be restored to zero, and may be left always in the last position to which it has been moved, since the wires 25—26 leading to the wiper arms s^a of the switch are cut-off at the relay contacts 23—24 when the apparatus is in disuse. The No. 1 and No. 2 program busses are connected to the output circuits of broadcast relay receivers 29—290 respectively, and the announcement bus 2700—2800 is connected to a local distributing apparatus or amplifier 25 with a microphone Mf. The announcement set as a whole is connected symbolically only at AS. This position or equipment on the radio switchboard corresponds to the information operator's position on a telephone switchboard.

The operation of Fig. 5 is as follows: the subscriber calls as before, by making short closures of his line at the key 63, after inserting the plug P^2 in the jack J^2 . These short closures flash both the telephone and the radio switchboard lamps L^2 (Fig. 1) and 36 (Fig. 2). Connection is established by the radio operator inserting the plug 10 in the jack 9, or closing the equivalent switch. It may be mentioned in passing that any form of switch may be substituted for the jack 9, even to a relay controlled from a keyboard position by the operator, without departing from the invention. Divers forms of switches suitable for this purpose will occur to those skilled in the art, such as for example, a key switch of the general type of operator's ringing and listening key, having pivoted lever and a rocking wedge passing up and down between the pairs of contact springs, to open and close them. Such a switch may have practically any desired number of contacts, and requires no separate plug to operate it. The additional contacts are available for a number of purposes, including the cut-off of battery current from the magnet 420 when the parts are in disuse, which should be done as a matter of good practice, although not necessarily a part of the invention.

The subscriber's line having been thus connected with the central office wires 1—2, the relay 42 is included therein, and comes under the control of the subscriber. Since his line circuit remains closed after signaling at

the key 63, the relay 42 is energized, and closes all its contacts 310, 34, 24, 23 and 351. This connects the input or grid side of the line tube 37 to the switch wipers s^a , and also closes the filament circuit through battery F^2 . The three pairs of bank contacts s — s' — s'' represent a suitable number to contain all the program busses, and if it be desired to use a circle of contacts greater in number than the number of busses, then the latter may be repeated several times in passing around the circle. The switch wipers are left where they stand without restoring, so that when the subscriber has become connected through the tube 37 to the switch S he is immediately on some bus. If it is a program bus and he desires to select some particular item, he can by means of his key 63 propel the switch arms s^a until they come in contact with the bank contacts s^2 connected to the announcer's bus 2700—2800, and by listening, he will hear a continuous announcement of the items then upon the bus, the items to follow, the numbers or call letters of the stations from which the said items are being sent, and any other interesting information connected with the same. I consider this separate announcement bus, corresponding to an information operator's position, to be important as well as novel and original with myself and shall claim the same accordingly. Having ascertained what program and what items he desires to hear, the subscriber is able to start from zero and step the switch around to the desired busses such as 27—28, 270—280, etc. Thus the announcer's bus, when reached, which is always easily distinguishable, serves a double purpose, being also the zero bus from which the program busses are counted. If the subscriber has a loud speaker, and desires some particular item for which he has to wait, he may leave his switch connected with the announcer's bus until the time for making connection arrives, and in the meantime will receive all the announcements, with such matters of entertainment and information as may be intercollated therebetween. This means that during the entire broadcasting period, the announcements will be going on, interspersed with comments, explanations, etc. To these may be added news items and the like if desired, but I think it preferable to have these on a separate program bus leaving the announcer's bus to fulfill the function of an information operator only.

I have shown herein in Fig. 1 a meter connected to the test or cut-off wire 3, and for telephone recording this would be operated in the usual manner. For metering the radio service, I have shown in Fig. 2 the commutator and high voltage generator adapted to meter operation, in a manner familiar to those skilled in the art. This generator

is only connected with the relay 42 is energized and the commutator closes the circuit, which occurs at intervals during the time the subscriber's line is connected to the radio bus or busses. I have also shown a meter operating generator and commutator in Fig. 5, but it is to be understood that in the latter case, where there is selection of program, there should also be selection of a charging rate corresponding thereto; which means that there would be a separate meter commutator for each of the program busses, brought into connection with the contacts 34 and test wire 3 through bank contacts of the switch S, corresponding to the program contacts $s-s'$ — s^2 associated therewith, by adjusting these separate commutators to different speeds or rates of operation, the metering can be made variable according to the program being received. This is described and claimed in my prior copending applications, Serial No. 746,357, filed October 28, 1924, and Serial No. 746,358, filed October 28, 1924. Any method of differential metering may be employed for this purpose without departing from the scope of my invention.

It should be stated here that while I have developed herein a specific arrangement of the apparatus and circuits for the purposes stated, there are a number of modifications which I contemplate and shall not describe herein specifically, because they will form the subject matter of separate applications.

I wish to state herein however, that according to one modification, the line signal lamp 36 on the radio switchboard, and the line vacuum tube 37 on the same, may be and preferably are, made one and the same unit. The tubes 37 are used as amplifiers, which means that they will be lighted to somewhat greater brilliancy than if used as detectors, hence under proper conditions of lighting and arrangement, they may very well be used for visible signals. According to this arrangement, when a subscriber calls radio, he will flash the filament of the tube 37, which gives the visible signal to the radio operator that he desires radio connection.

The tube 37 for such use would be located in a designated and determinate position to indicate the identity of the line, and would preferably be associated with the line switch 9. When the plug is in or throws the switch 9, the result would be to cut off the direct line connection with the tube 37, and substitute the working circuits through the tubes as shown in Fig. 5. In clearing out the subscriber may then again flash the filament of the tube 37, which with the switch 9 closed, would indicate disconnection.

While I have herein described and illustrated the use of audio frequencies for distribution to the subscribers over their wired line circuits the invention is not limited to

such frequencies, but may employ also super-audio frequencies, so long as they are suitable for line transmission. In the work heretofore done by Major General Squier and others, frequencies ranging from 25 to 100 kilocycles per second have been found suitable for this purpose. In order to make such frequencies available for distribution among the subscribers in the present system, the connections from the central station receiving and relay distributing apparatus remain practically the same, as those described and shown in Figs. 2 and 5, the input or grid circuit of the individual line tube 37 also remaining the same. The repeating coil connection to each line must either be supplemented or replaced however by a filter connection, preferably permanent, which will permit superaudio frequency currents to be transmitted from the plate circuit of the tube to and over the line circuit to the subscriber's station, while the battery current from the battery B will simultaneously flow over the subscriber's line for signaling and talking purposes of the subscriber. At the subscriber's station, complementary connections must be made, and a detector radio set must be connected to receive superaudio currents over the line, while the telephone elements are connected, preferably in parallel, to receive the battery current and transmit and receive audio frequency waves. Such an arrangement is shown as to its principles in Letters Patent granted me January 6, 1925, No. 1,552,362, to which reference is had for further explanation of the principles involved.

The arrangement of Figs. 6 and 7, is the same as that of Figs. 2 and 3, except that the relays 29 and 89 (Fig. 6) are arranged to take broadcast matter at their input terminals at line frequencies such as audio or modulated superaudio, and the relay transmitter 39 (Fig. 7) is arranged to transmit at such line frequencies and has its output circuit connected to multiples 351, 352 through which its output is distributed to the relays 29 or 89 of different local distributing stations such as that of Fig. 6 by means of circuit connections made through connecting cords or links such as 353 (Fig. 7) trunk 150, cord 57 (Fig. 6) and jack 55. In order to keep the power output proportional to the number of connected outgoing trunks, each link circuit 353 is preferably provided with an amplifier. It is preferable to transmit from the district station to the central station by superaudio or carrier current in which case the relays 29 at the central stations (Fig. 6) are preferably arranged to detect the same and supply the audio currents amplified to the bus 27—28.

What I claim is:

1. In a system of radio broadcast distribution, a plurality of subscribers' stations di-

vided into a plurality of groups, a district broadcast station having broadcast receiving apparatus and wired broadcast distributing means common to said groups, a central station for each group having receiving means for receiving the broadcast from said common district station, amplifying means arranged to connect the receiving means of a central station with said distributing means, and amplifying means arranged to connect each subscriber's station with the receiving means at the central station of its group.

2. In a system of broadcast distribution, a district broadcast service station, a plurality of local central stations, a group of subscribers' stations for each central station, circuit connections between said central station and its group of subscribers' stations, circuit connections between said district station and said central stations, means at the district station for amplifying, and transmitting broadcast matter to said central stations over the circuit connections between the same, and means at a central station for amplifying and relaying the broadcast matter received thereat to its subscribers' stations over the said circuit connections between the same.

3. A system for the broadcast distribution of signals comprising the following instrumentalities: a plurality of subscribers' stations distributed over an extended area and divided into groups, a central station for each group, wires interconnecting each central station with the subscribers' stations in its group, a district station common to all the groups, wire circuits connecting the district station with the several central stations, means at the district station for receiving broadcast matter from other stations and means for amplifying and distributing the same over said wire connections to the several central stations, means at each central station for amplifying the broadcast matters re-

ceived thereat, and means for connecting the subscribers' wires to said amplifying means whereby the receiving and distribution of broadcast matter is effected through a single station, but its amplification in distribution is proportional to the number of stations served.

4. In a system of radio broadcast distribution, a plurality of subscribers' stations divided into a plurality of groups, a central station for each group, a district broadcast station having wire trunks extending to the several central stations, means at said district station to produce modulated carrier current suitable for transmission over the wire circuits, means for connecting the same through amplifiers to said wire trunks, program busses forming terminals of said trunks at the several central stations, and means to connect the subscribers' lines to said program busses through amplifiers.

5. The combination of a central station and a subscriber's station, with line wires interconnecting them, a vacuum tube amplifier at the central station associated with the said line wires, a source of broadcast matter, and means to connect the subscriber's line thereto through said amplifier, and other means controlled by the subscriber for controlling the filament circuit of said vacuum tube to flash and put out the same, by way of signaling.

6. In a system of the class described, a subscriber's station and a central station, a vacuum tube at the central station having a filament circuit, means for transmitting from the central station through said tube to the subscriber's station and means controlled by the subscriber to produce changes in said filament circuit for the purpose of signaling to the central station.

In testimony whereof I hereunto affix my signature.

EDWARD E. CLEMENT.
